UNITED STATES PATENT OFFICE.

JOHN FREDERICK KAISER, OF BARTLESVILLE, OKLAHOMA.

SIGN.

1,212,069.

Specification of Letters Patent.

Patented Jan. 9, 1917.

Application filed December 14, 1915. Serial No. 66,742.

To all whom it may concern:

Be it known that I, JOHN F. KAISER, a citizen of the United States, and a resident of Bartlesville, in the county of Washington and State of Oklahoma, have invented an Improvement in Signs, of which the following is a specification.

One of the objects of the invention is to provide a sign for show window display, in which removable display cards, made of ordinary paper, are used in an illuminated sign which will flash from one color to another at regulated intervals, and so attract the attention of prospective customers.

15 A further object of my invention is to produce a sign provided with two lamps of different colors so selected and in such relation to a reflector of peculiar construction, that when both lamps are burning brightly, the rays of light from one will be blotted out by the light from the other, and when the latter lamp is dimmed, the sign will be of the color of the first lamp.

20 A still further object of my invention is to provide automatic electro-thermally controlled means for so dimming one of the lamps at regulated intervals.

25 With such objects in view, and others which will appear as the description proceeds, the invention comprises various novel features of construction, and arrangement of parts which will be set forth with particularity in the following description and claims appended hereto.

30 In the accompanying drawings, which illustrate one embodiment of the invention, and wherein like reference characters indicate like parts, Figure 1 is a perspective view of my improved sign in position in a show window. Fig. 2 is a vertical side sectional view of the device. Fig. 3 is a horizontal section on the line 3—3 of Fig. 2. Fig. 4 is a part elevation of my improved sign with the display card holder removed.

35 In the drawings, the lamp box, which is formed of sheet metal highly polished on its inner surface to form a reflector, comprises a rectangular rear wall 1, and outwardly flaring sides 2. A rectangular rim 3, suitably stiffened at its front edge as shown at 4, is riveted to the front of the sides 2 and forms a frame for the reception of the display card holder. The lamp box is supported by two short front legs 5, secured to the lower side of the rim 3, and a longer rear leg 6 secured to the lower

side of the lamp box. The legs are of a length adapted to support the lamp box in a slightly rearwardly inclined position, so that the sign may be readily seen by a passerby.

40 The display card holder comprises a rectangular frame 7, having a rearwardly projecting flange 8 which exactly fits within the front opening of the lamp box. A glass front 9 is held in this frame by a beading 10 secured to the inner side of the flange 8. The sign which it is desired to display is formed upon a sheet of semi-transparent paper 12 which fits within the beading 10 70 behind the glass. This paper sign is removably held in position by a spring metal rod 11, which fits in the angle formed by the glass and the beading 10, and clamps the paper sign in position. By this construction it will be seen that the holder for the display card may be quickly removed from the lamp box, and the display card easily withdrawn and another inserted in its place by removing the clamping rod 11.

45 Standard electric light sockets 13 and 14, are secured one above the other, to the rear wall 1 of the lamp box. Electric light bulbs of different colors are held in these sockets, the colors selected being such, that when 85 both lamps are burning brightly the light rays from the lower bulb 15 will blot out the colored rays from the upper bulb 16.

50 In the embodiment of my invention shown in the drawings, I have used a 90 white lower bulb 15, and an upper bulb 16, one half of which is colored yellow and the other half purple with the edges of the two colors blended together, but it is obvious that many other combinations, red 95 and green, red and white, green and white, for example, could be used. A light shield 17, preferably of metal, is placed over the front of the upper bulb to prevent spots of light from the same showing through the semi-transparent sign. An electrical appliance 18 of ordinary construction, comprising a rheostat and automatic thermally controlled means for alternatingly shunting a current through the rheostat and around the same, is secured to the inner side of the lamp box. This device is placed in the circuit of the lower lamp to automatically increase and decrease the current thereto at 100 regular intervals, and so flash the lamp 15 11. from a bright to a dim light, while the current supplied to the upper lamp remains

constant, and so maintains a bright light in the lamp 16.

Wires 20 and 21 secured to a connecting plug 22, are led into the lamp box through an opening 19 formed in the lower side thereof. The wire 21 leads to a binding post of the lamp 15 and thence to a post of the lamp 16. The wire 20 leads from the other binding post of lamp 16 to the binding post 23 of the current shunting apparatus, and thence to the plug 22. The binding post 24 of the automatic shunting apparatus is connected to the other post of lamp 15 by a short wire 25. The contact point 26 upon the shunting device, is in the form of a set screw, so that it may be adjusted to regulate the intervals between variations in the current.

From the foregoing description it is believed the operation of the device will be apparent. A sign with the desired advertisement painted thereon is placed in the holder which fits in the front of the lamp and the plug 22 is connected to a source of electrical current. The circuit through the upper lamp is uninterrupted so it will burn showing a steady bright purple and yellow light. The white lamp will first be dimmed, the current thereto being shunted through the rheostat, and the sign will, therefore, diffuse a blended yellow and purple glow. When the current to the white lamp is automatically shunted around the rheostat, the lamp will burn brightly, blotting out the blended rays from the upper lamp and diffusing a white light through the sign. These alternations in color effect will continue as long as the sign is supplied with current. The interval of time between flashes may be regulated by the set screw 26.

It will thus be seen that I have provided a sign of durable construction, adapted to use interchangeable inexpensive display cards, which will automatically flash from one color to another at regulated intervals.

I claim:

1. In a device of the character specified, a lamp box, a sign plate at the front of the said lamp box, lamps of different color within the said lamp box, reflectors for the said lamps, means for changing one of the said lamps from a dim to a bright light, the

other lamp being adapted to burn uniformly during operation, the said lamps being of such a color and so positioned relative to the said reflectors, that the sign plate will be of the color of the changing lamp when the same is burning brightly, and of the color of the other lamp when the changing lamp is dimmed. 55

2. A sign substantially as described, comprising a lamp box open at its front, a frame having a rearwardly projecting flange adapted to fit within the open end of the lamp box and support a transparent plate, a beading secured to the said flange and adapted to hold the said plate in position, a display sign formed of semi-transparent material in rear of the said plate and within the said beading, means for holding the semi-transparent sign in position, and means carried within the lamp box for illuminating the said sign. 60

3. In a sign of the character specified, the combination with electric lamps of different color, of an electric circuit through the said lamps, means for changing one of the said lamps from a dim to a bright light, the other lamp burning uniformly during operation, the said changing lamp being of such a color 70 as to obliterate when burning brightly the effect of the light from the other lamp. 75

4. A sign comprising a semi-transparent sign plate, a lamp in rear thereof burning uniformly during operation, a second lamp 85 coöperating therewith and adapted to obliterate the effect of the light from the first lamp through the said sign plate, and a light shield so positioned as to interrupt part of the rays of light from the first-mentioned lamp through the said sign plate. 90

5. In a device of the character specified, a sign plate, a lamp in rear thereof burning uniformly during operation, a second lamp coöperating therewith and adapted when burning brightly to obliterate the effect of the light from the first-mentioned lamp through the said sign plate, and means for changing the second lamp from a dim to a bright light. 95

JOHN FREDERICK KAISER.
